UNITED STATES PATENT OFFICE.

WILLIAM KIRKWOOD, OF CHICAGO, ILLINOIS.

BLOWPIPE.

1,029,691.

Specification of Letters Patent. Patented June 18, 1912.

Application filed March 6, 1911. Serial No. 612,664.

To all whom it may concern:

Be it known that I, WILLIAM KIRKWOOD, a citizen of the United States, and a resident of Chicago, in the county of Cook and State of Illinois, have invented certain new and useful Improvements in Blowpipes, of which the following is a full, clear, and exact specification.

This invention relates to improvements in blow pipes for directing the flame from a mixture of carbureted hydrogen (*i. e.* hydrogen saturated with a hydrocarbon) and oxygen, employed for the purpose of welding and severing bars, columns, beams and other articles of iron and steel, by directing their flame from a blow pipe against the point or line of surface thereof at which their severing is desired until melted apart.

Prior to my invention blow pipes, employed for the purposes above described, have been so constructed that their oxygen and carbureted hydrogen gases are respectively discharged in a single stream into a chamber, one of which streams is solid and surrounded by the other, so that their mixture is not as perfect as should be for obtaining the best effects of their flame, and, furthermore, the point at which these gases are ignited is so far removed from that at which they first come in contact with each other that when the force of these streams is below the maximum required for the successful use of their flame, there is a constant tendency of the flame to back-flash, and this increasingly with the reduction in force, with the result that an effective operation of the pipe is prevented by internal melting, not infrequently to a degree destructive of the further use of the pipe.

The object of my invention is a blow pipe, adapted for the purposes above described, so constructed that it is impossible for a flame, produced from a mixture of oxygen and carbureted hydrogen, to back-flash into the pipe at any force it may have, however great or small that force may be, and by such means as makes it possible and practical to combine with carbureted hydrogen another material, such for example as bisulfid of carbon, and thereby the production of a gas better adapted for the purposes of a welding and particularly a severing flame, and which has heretofore been prohibited because of its substantially greater tendency to produce a back flame than that of a flame

produced by carbureted hydrogen with oxygen.

A further object of my invention is to have a blow pipe so constructed that the internal parts thereof are conveniently accessible for the removal of possible obstructions at any point, and at the same time reduce its cost and simplicity of construction to a minimum.

With these ends in view, my invention finds embodiment in certain features of novelty in the construction, combination and arrangement of parts by which the said objects and certain other objects are hereinafter attained, all as fully described with reference to the accompanying drawings, and more particularly pointed out in the claims.

In said drawings: Figure 1 illustrates in section and on an enlarged scale a blow pipe 75 nozzle embodying my invention. Fig. 2 is an enlarged transverse section on the line 2—2 of Fig. 1 looking in the direction of the arrows; and, Fig. 3 is a section on the line 3—3 of Fig. 1 looking in the direction of the arrows.

Similar characters of reference indicate the same parts in the several figures of the drawings.

4 indicates a pipe screwed into an elbow 85 5, in which is a chamber 6, to which, from a suitable source, there is supplied, through the pipe 4, either oxygen or carbureted hydrogen. The chamber 6 is closed at one end by a perforated plate 7 in a coupling 8, internally forming a chamber 9, to which either oxygen or carbureted hydrogen may be supplied through the pipe 10 from any suitable source, the supply therethrough being regulated by a stop cock 11 in the pipe 90 95 10 and in the pipe 4 by a stop cock 12.

Screwed into the end of the coupling 8 is a nozzle 13, into which projects a plurality or series of pipes 14 surrounding a central pipe 15, terminating at a point shortly removed from the end of the nozzle, the bore of the nozzle being tapered, as indicated at 16, and thereby forming an annular chamber about the pipes facilitating the discharge of the contents of the chamber 9. 105 The tubes 14 and 15 are tight in the plate 7 and open into the chamber 6, thereby receiving and discharging the contents of said chamber, the arrangement of the tubes being such as to provide between them pas- 110

sages for the discharge of the contents of the chamber 9, and with the result that the contents of chambers 6 and 9 are isolated from each other until they meet next the 5 open end of the nozzle. All of the tubes 14 are in contact with each other beyond the base of the nozzle for a portion of their length, until well toward their outer ends, and the central tube 14 has inserted therein 10 and projecting therefrom a tube 15 to form an annular space surrounding the central tube 14, facilitating the discharge of the surrounding gas or liquid, as may be, at the extreme end of the tubes, and of which it 15 may be said in practice they are so small that their openings are substantially needle-like, for the reason that the best mixture of the two gases is obtained when reduced to a spray-like condition, and they are dis- 20 charged with the greatest possible force at their point of ignition, which is immedi- ately adjacent the ends of the tubes.

While it would be no substantial departure from my invention to extend the tubes 25 14 and 15 to a point flush with the end of the nozzle 13, I find in practice that it is better to have the tubes sufficiently short of this point to form a chamber 17, for by so doing atmospheric air is better excluded 30 from the flame and the flame directed in a solid form against the opposing surface to which it is applied, and, in this connection it is proper to observe that provision is made for adjusting the depth of this cham- 35 ber by the screw threading of the nozzle into its coupling.

The essential feature of my invention resides in the maintaining of the two gases separated up to the instant that they are 40 ignited, and discharging them in fine jets in the presence of each other, whereby they are most effectively intermingled, and at the same time and by reason of these divided jet openings a back flame of these gases to 45 the internal injury of the blow pipe is rendered impossible. It is, therefore, not es-

sential to these principal features of my invention that the several parts should be detachable, or that the chambers receiving their contents from supply pipes should be 50 of the form and arrangement shown.

Having described my invention, what I claim and desire to secure by Letters Patent is:—

1. A blow pipe for the purposes de- 55 scribed, comprising in combination a series of jet pipes, a number of jet passages be- tween and inclosed by the walls of said pipes, separate receiving chambers for said pipes and passages, and means for supply- 60 ing different gases to said chambers, sub- stantially as described.

2. A blow pipe for the purposes de- 65 scribed, comprising in combination a nozzle, a series of jet pipes inclosed by said nozzle and terminating a short distance from the end thereof, a series of jet pas- 70 sages between and inclosed by the outer walls of said jet pipes, and means for sup- plying different gases to said pipes and pas- sages, substantially as described.

3. A blow pipe for the purposes described, comprising in combination a nozzle, a plu- 75 rality of jet pipes within said nozzle, con- tacting with each other and terminating to- ward the outer end thereof, a series of jet passages between and inclosed by the outer walls of the jet pipes, and separate supply chambers for said pipes and passages for containing different gases simultaneously 80 discharged and intermingled in spray-like streams in the presence of each other about the end of the nozzle, substantially as de- scribed.

In witness whereof, I have hereunto set 85 my hand and affixed my seal, this 1st day of March, A. D. 1911.

WILLIAM KIRKWOOD. [L.S.]
